US0D1047151S

(12) **United States Design Patent** (10) **Patent No.:** **US D1,047,151 S**
(45) **Date of Patent:** **** Oct. 15, 2024**

(54) **ULTRASOUND THERAPY DEVICE**

(71) Applicant: **Wenzhou Xingteng Electronic Technology Co., Ltd.**, Zhejiang (CN)

(72) Inventor: **Haisa Lin**, Zhejiang (CN)

(**) Term: **15 Years**

(21) Appl. No.: **29/956,055**

(22) Filed: **Aug. 5, 2024**

(51) **LOC (14) Cl.** **24-02**

(52) **U.S. Cl.**

USPC **D24/187**

(57) **CLAIM**

The ornamental design for a ultrasound therapy device, as shown and described.

DESCRIPTION

FIG. 1 is a front, top and right-side perspective view of the ultrasound therapy device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, bottom and left-side perspective view thereof.

The broken lines throughout the drawing figures depict portions of the ultrasound therapy device that form no part of the claimed design.

1 Claim, 8 Drawing Sheets
